CULOTTE GARMENT

Albert A. Wilson, New York, N. Y.

Application December 23, 1937, Serial No. 181,295

2 Claims.

(Cl. 2—72)

This invention relates to new and useful improvements in a culotte garment.

The invention contemplates characterizing the culotte dress by the fact that it has a skirt portion and a waist portion and that it is of one piece or two piece construction.

The invention has for a further object, the construction of a culotte dress which is characterized by a skirt portion constructed in a particular manner.

The invention proposes to provide a skirt portion with a tubular body having a crotch and a pair of leg portions, and an opening extending from the crotch to the top thereof, and an arrangement for securing the leg portions together and for closing the said opening.

Specifically, the invention proposes the provision of cooperative fasteners extending along adjacent portions of the leg portions and continuing along the sides of said opening.

Another one of the objects of this invention is to use a slide controlled hook fastener as the cooperative fastening means.

Still further it is proposed to arrange the slide of the fastener in a manner so that when it is at the bottom of the culotte dress the leg portions are held together and the said opening is closed. It is proposed to so arrange the parts that the control slide may be moved upwards to the crotch area to open the secured together leg portions. It is further proposed that the slide be movable from the crotch portion to the top of the culotte dress to open said opening.

Still further the invention proposes the provision of means in the vicinity of the crotch portion of the culotte dress to normally limit the upward motion of the control slide to the crotch area only.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a front elevational view of a one piece culotte dress constructed according to this invention.

Fig. 2 is a front elevational view of a waist portion of a two piece culotte dress constructed according to this invention.

Fig. 3 is a perspective view of the skirt portion for the waist portion shown in Fig. 2.

Fig. 4 is a horizontal sectional view taken on the line 4—4 of Fig. 3.

Fig. 5 is a horizontal sectional view taken on the line 5—5 of Fig. 3.

Fig. 6 is a vertical sectional view taken on the line 6—6 of Fig. 4.

Fig. 7 is a perspective view of the skirt shown in Fig. 3 but illustrated with the straps closed.

Fig. 8 is a rear elevational view of the skirt portion of a culotte dress constructed according to another embodiment of the invention.

In Fig. 1, a one piece culotte dress embodying this invention is illustrated. This culotte dress has a waist portion 10 and a skirt portion 11. The skirt portion has a tubular body 11^a, a crotch 15 11^b, and leg portions 11^c. An opening 12 extends along the front of the dress from the crotch portion 11^b to the top edge of the skirt portion and then continues and connects with an opening 12^a at the front of the waist portion. Lines of 20 cooperative fasteners 13^a and 13^b extend along adjacent portions of the leg portion 11^c and continue along the sides of the front openings 12 and 12^a.

The waist portion 10 is secured to the top of 25 the skirt portion 11. The junction is provided with a belt 14. The particular design of the blouse 10 forms no part of the invention and is for illustrative purposes only. This is also true as regards the details of the skirt 11. For example the pleats 15 are purely a matter of design.

The cooperative fasteners 13^a and 13^b comprise interengageable hooks of the "zipper" type. These fasteners are controlled by a slide 13^c. 35 The parts are so arranged that when the slide is at the bottom, as illustrated in Fig. 1, the fasteners connect with each other. The control slide 13^c may be moved upwards to the crotch area 11^b to disconnect the leg portions from each other. The dress may now be worn in this condition. The control slide 13^c may be moved further upwards to the upper end of the opening 12^a to open the front of the skirt and the front of the waist.

A pair of straps 16 are secured at one of their ends to the opposite sides of the material of the skirt along the opening 12, at the crotch area 11^b. These straps 16 may be tied together so as to prevent the control slide 13^c from moving further 50 up than this particular point. These straps 16 therefore limit upward motion of the control slide 13^c to a position in which the leg portions are disconnected. The straps 16 prevent further upward accidental motion of the slide which 55

would open the front of the dress. The control slide 13c has a handle portion 13cc formed with an opening 11. One of the straps 16 may be slipped through this opening 11 before the straps are tied together. This securely holds the slide control. It is then necessary that the straps 16 be untied before it is possible to move the slide control upwards or downwards.

In Figs. 2-7 inclusive, another embodiment of the invention has been disclosed. In these figures the culotte dress comprises a waist portion 10' and a skirt portion 11'. The waist portion 10' is formed separate from the skirt portion and has a crotch anchorage element 18 to hold it down. This anchorage element comprises merely reduced portions from the front and back adapted to be releasably secured together with a button and button hole construction 19. The skirt 11' is adapted to be worn over the lower end of the waist portion 10'.

The skirt portion 11' has a waistband 14' along its top edge which is releasably secured closed by a button and button hole construction 20. The skirt 11' is formed with a tubular top body 11a, a crotch portion 11b, and a pair of leg portions 11c. An opening 12 extends from the crotch portion to the top of the skirt. Lines of cooperative fasteners 13a, 13b are extended along adjacent portions of the leg portions 11c and along the sides of the opening 12. In Fig. 8, the skirt is shown in the open position. In this view the crotch portion 11b is readily seen. In Fig. 6, the crotch portion 11b is also clearly illustrated. In other respects this form of the invention is similar to the previous form and similar parts may be identified by corresponding reference numerals.

In Fig. 8, another embodiment of the invention has been disclosed in which a skirt 11'' is shown provided with a tubular body 11a, a crotch portion 11b, and leg portions 11c. This view is a rear view of the skirt. This skirt has an opening 12'' extended from the top of the crotch portion 11b to the top of the skirt. A line of cooperative fasteners 13a and 13b are extended along adjacent back portions of the leg portions 11c and continue along the sides of the opening 12'' to the top of the skirt. These cooperative fasteners are controlled with a control slide 13. At the crotch area there are straps 16 attached along opposite sides of the opening 12''. These straps 16 are shown tied together in a bow to prevent pulling up of the control slide 13c above this point. The control slide is also formed with an opening 11 through which one of the straps 16 may be slipped for tying the slide in this position when desired. In other respects this form of the invention is similar to the previous forms and similar parts may be identified by corresponding reference numerals.

It is to be understood that this garment may be of any desired style and size worn by women and children. It may be formed into a bathing suit, lounging pajama and the like.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a culotte garment, a tubular body having a crotch and a pair of leg portions and an opening extending from the crotch to the top thereof, cooperative slide fasteners extending along portions of said leg portions and continuing along the sides of said opening, a control slide for said slide fasteners and movable downwards to close said slide fasteners, and means at the junction of said leg portion and said crotch for limiting upward movement of said control slide for holding said opening closed with said leg portion free from each other, comprising a strap attached to each side of said opening at said junction and said straps being extendible across said slide fasteners and engageable with each other for arresting upward movement of said control slide and so prevent said opening from being accidentally opened.

2. In a culotte garment, a tubular body having a crotch and a pair of leg portions and an opening extending from the crotch to the top thereof, cooperative slide fasteners extending along portions of said leg portions and continuing along the sides of said opening, a control slide for said slide fasteners and movable downwards to close said slide fasteners, and means at the junction of said leg portion and said crotch for limiting upward movement of said control slide for holding said opening closed with said leg portion free from each other, comprising a strap attached to each side of said opening at said junction and said straps being extendible across said slide fasteners and engageable with each other for arresting upward movement of said control slide and so prevent said opening from being accidentally opened, and a handle on said control slide having an opening through which one of said straps may be passed before said straps are engaged for also limiting downward movement of said control slide, whereby said control slide may be limited against vertical movement in either direction for preventing said opening from being accidentally opened and said leg portion from being accidentally closed.

ALBERT A. WILSON.
